UNITED STATES PATENT OFFICE.

MARTIN A. HAYWARD, OF ELMWOOD, MASSACHUSETTS, ASSIGNOR OF
ONE-HALF TO ALVA P. POOLE, OF BROCKTON, MASSACHUSETTS.

HANDLING-HORSE FOR SHOE-UPPERS.

SPECIFICATION forming part of Letters Patent No. 722,018, dated March 3, 1903.

Application filed April 15, 1902. Serial No. 103,062. (No model.)

To all whom it may concern:

Be it known that I, MARTIN A. HAYWARD, a citizen of the United States, residing at Elmwood, in the county of Plymouth and State of Massachusetts, have invented certain new and useful Improvements in Handling-Horses for Shoe-Uppers, of which the following is a specification.

This invention relates to boot and shoe making, and has special reference to the means for handling the "tops" and vamps, constituting the complete uppers, during the process of manufacture.

To this end the invention primarily contemplates a handling-horse for shoe-uppers comprising means for conveniently and rapidly handling in pairs the separate parts of the uppers, as well as the complete uppers, so as to greatly facilitate carrying out the different steps pursued in the manufacture of boots and shoes and dispensing with a large amount of the labor involved in maintaining the uppers and the parts thereof properly paired while the articles in different stages of completion are carried from one department to another of the manufacturing establishment.

The present invention is intended to be essentially a labor-saving device by entirely dispensing with the necessity of tying the uppers or parts of uppers together by strings or cords, while at the same time providing for always maintaining the different parts in a properly-paired relation, and facilitating the convenient handling or removing of a "case" of uppers or upper parts from one department to another without the objectionable hauling about of boxes in which the cases of twenty-four pairs are usually made up.

With these and many other objects in view, which will more readily appear as the nature of the invention is better understood, the same consists in the novel construction, combination, and arrangement of parts, which will be hereinafter more fully described, illustrated, and claimed.

The essential features of the invention are necessarily susceptible to a wide range of modification without departing from the spirit or scope of the invention; but a pre-

ferred embodiment thereof is shown in the accompanying drawings, in which—

Figure 1 is a perspective view of an upper-horse shown in its operative position upon the bench of the workman adjacent to the shoe-making machine and shown partially filled with paired shoe-tops, the latter being indicated in dotted lines. Fig. 2 is a perspective view of the horse, indicating the position of its members when fastened together after being completely filled and ready to be transferred from one department or room to another.

Like reference-numerals designate corresponding parts throughout the figures of the drawings.

In carrying out the invention the device as an entirety essentially consists of a spring-wire body 1. This spring-wire body is preferably formed of a single length of spring-wire of sufficient stoutness for the purpose intended and bent upon itself to provide the separate side standards 2, which constitute what may be properly termed "upper-carriers," said standards being designed to respectively receive thereon the rights and lefts of the uppers or upper parts. The said side standards or upper-carriers 2 are arranged in sufficient spaced relation to permit of the uppers or upper parts being readily slipped over the same, and the standards are also preferably in their normal condition arranged in substantial parallelism, so that each of the same is equally available to the operator for placing on or removing a right or left upper or upper part. At the lower end or base the spring-wire body 1 of the device is preferably twisted upon itself to provide a combined supporting-stem and handle 3, adapted to detachably fit within the socket 4 of a socket member 5, which is designed to be seated flush within the operator's bench adjacent to the stitching or shoe-making machine, so that the entire device is within convenient reach of the operator.

The side standards or upper-carriers 2 are normally disconnected at their free ends, over which the uppers or upper parts are passed both in filling and emptying the horse; but when both standards or carriers 2 of the horse

- are entirely filled with uppers or upper parts the free ends of the latter are adapted to be sprung together and detachably interlocked. This may be provided for in a number of ways, 5 but preferably by forming the standards or carriers at their upper or free ends with reversely-disposed catch hooks or loops 6, which may be readily engaged and disengaged during the manipulation of the horse.
- 10 It will here be noted that one of the hooks 6 forms a substantially vertical keeper, while the other forms a substantially horizontal catch for detachable engagement with the keeper. This arrangement is a very important 15 feature of the present invention, as it materially facilitates the engagement and disengagement of the hooks.
- In the first instance the side standards or carriers 2 of a horse are filled, respectively, 20 with the rights and lefts of the shoe-tops. After being thus filled with tops the horse is closed by the locking of the catch-hooks 6 and is removed to the bench where the vamps are to be stitched to the tops. The tops are 25 then removed one pair at a time and the vamps stitched on, after which the complete uppers are placed on another adjacent horse. The latter horse when filled is likewise closed and removed to the bottoming-room, where 30 the uppers are removed a pair at a time and the bottoms or soles attached. It will thus be seen that the herein-described horse provides simple and convenient means for always maintaining the uppers or upper parts 35 properly paired without resorting to the use of the usual strings, while at the same time permitting the uppers or upper parts being handled in the most convenient and expeditious manner.
- 40 From the foregoing it is thought that the construction, use, and many advantages of the herein-described horse will be readily apparent to those familiar with the art, and it will also be understood that various changes 45 in the form, proportion, and minor details of construction may be resorted to without departing from the spirit of the invention or sacrificing any of the advantages thereof.
- Having thus described the invention, what 50 is claimed, and desired to be secured by Letters Patent, is—
1. An upper-horse, having a pair of spaced upright upper-carriers, the space between the same being unobstructed from top to bottom 55 to permit of uppers being placed astraddle of the respective carriers, and means for detachably connecting the tops of the carriers to permit displacement of the uppers.
  2. An upper-horse, having a pair of spaced 60 upright upper-carriers, the space between the carriers being unobstructed from top to bottom to permit of uppers being placed astraddle of the respective carriers, and the upper end of one of the carriers having a catch for detachable engagement with the other member to prevent displacement of the uppers.
  3. An upper-horse of the class described comprising a spring-wire body having separate carriers respectively for rights and lefts, said carriers having free ends adapted to be 70 detachably interlocked.
  4. An upper-horse of the class described comprising a spring-wire body having at one end a pendent combined supporting-stem and handle, and a pair of side standards rising at 75 opposite sides of the stem and constituting carriers respectively for the rights and lefts of the uppers or upper parts.
  5. An upper-horse of the class described comprising a spring-wire body having at its 80 base a combined handle and supporting-stem and also provided with opposite side standards constituting carriers respectively for the rights and lefts of the uppers or upper parts, said standards being provided at their free 85 ends with catch members adapted to be detachably sprung into interlocked engagement.
  6. In a device of the class described, the combination with a socket member, of an upper-horse comprising means for separately 90 holding the rights and lefts of the uppers or upper parts and provided at its base with a stem adapted to be detachably engaged in said socket member.
  7. An upper-horse, embodying a pair of up- 95 right spaced standards forming upper-carriers, the space between the standards being unobstructed from top to bottom, the upper end of one of the standards being formed into a keeper, and the upper end of the other 100 standard being formed into a hook-shaped catch for detachable engagement with the keeper to prevent displacement of the uppers, one of the standards being elastic to permit of the catch being engaged with the 105 keeper and to return said standard to its normal position when the catch is disengaged from the keeper.
  8. An upper-horse, comprising a substan- 110 tially V-shaped wire body, the upstanding members of which form elastic upper-carriers and are separated by an unobstructed space to permit of uppers being spaced astraddle of the carriers, the upper ends of the carrier members being bent into hooks for mutual 115 detachable engagement, and a stem pendent from an intermediate point of the transverse base portion of the body.
  9. An upper-horse formed from a single length of wire which is bent intermediate of 120 its ends with its opposite portions adjacent to the bend intertwined to form a stem, the wire members being extended outwardly in opposite directions from the upper end of the stem and thence bent upwardly to form 125 spaced standards, the upper end of one of the standards being bent into a substantially vertical hook-shaped keeper, and the upper end of the other standard being bent into a substantially horizontal hook-shaped catch 130 for detachable engagement with the keeper.
  10. An upper-horse, embodying a pair of

spaced upright flexible standards forming upper-carriers, the upper end of one standard being bent into a substantially vertical hook-shaped keeper, and the corresponding 5 end of the other standard being bent into a substantially horizontal hook-shaped catch for detachable engagement with the keeper.

In testimony whereof I affix my signature in presence of two witnesses.

MARTIN A. HAYWARD.
